UNITED STATES PATENT OFFICE.

FRANK H. WOOD AND FRED C. BARNARD, OF ITHACA, NEW YORK.

ENGINE.

Application filed July 3, 1925. Serial No. 41,338.

This invention relates to internal combustion engines of the four cycle type and has for an object the provision of a multi-cylinder engine constructed and arranged in compact form so as to occupy a relatively small space.

Another object of the invention is the provision of an engine of this type which will develop a relatively high horse power in proportion to its size.

Another object of the invention is the provision of a multi-cylinder engine in which the cylinders are arranged in double formation or end to end with the pistons of two cylinders mounted upon a single piston rod, novel means being provided for insuring true longitudinal reciprocatory movement for the rod so as to reduce liability of "piston slap".

Another object of the invention is the provision of novel means for operating the engine valve, the said means being especially adapted for an engine of the type illustrated.

With the above and other objects in view, the invention further includes the following novel features and details of construction, to be hereinafter more fully described, illustrated in the accompanying drawings and pointed out in the appended claim.

In the drawings:—

Figure 1 is an elevation of an engine constructed in accordance with the invention, parts being broken away and shown in section and other parts removed.

Figure 2 is a vertical central sectional view.

Figure 3 is an elevation at right angles to Figure 1 with the crank case omitted.

Figure 4 is a top plan view with the outer cylinder head removed.

Referring to the drawings in detail wherein like characters of reference denote corresponding parts, the engine as shown comprises a casing which includes spaced parallel cylinders 10 which are preferably surrounded by a water jacket 11, while the latter is in communication with jackets 12 and 13 provided in inner and outer cylinder heads 14 and 15 respectively. The cylinders 10 are of double formation in that they provide compression and explosive chambers 16 at their opposite ends, ignition devices or spark plugs 17 being also provided at each end of the cylinders 10 so as to ignite the compressed gases.

The cylinder head 15 is removably se-

cured to the engine block by means of bolts or studs 18, while the head 14 is likewise secured by bolts or studs 19 so that both of the heads may be removed. The water jacket 60 of the head 14 is provided with an inlet port 20 while the water jacket of the head 15 is provided with an outlet port 21 so that the water jacket may be included in a suitable water cooling system. 65

Entering the cylinders through the head 14 are piston rods 22 which have spaced oppositely disposed pistons 23 secured thereon. These rods pass through suitable packing glands 24 provided in the head 14, so that 70 the escape of compression from the inner chambers 16 will be prevented. The pistons 23 may be provided with suitable packing rings.

In order to insure true axial reciprocatory 75 movement of the rods 22, their inner ends are connected to crossheads 25 which operate between crosshead guides 26, the latter being secured to the opposite side walls of a housing 27. Connected to the crossheads 80 25 by means of wrist pins 28 are connecting rods 29 and the latter are in turn secured to a crank shaft 30. The shaft 30 is mounted in suitable bearings arranged within the housing 27 and this housing includes removable plates 31 to permit access to its interior. 85

Each end of the cylinders 10 is provided with inlet and exhaust ports 32 and 32^a which are arranged upon opposite sides of 90 the cylinders. These ports are in communication with the cylinders 10 through passages 33 and 33^a and are controlled by poppet valves 34. The stems of the valves 34 are surrounded by springs 35 which act to 95 normally hold the valves in closed position, the stems at the outer ends of the cylinders being engaged by plates 36 which are pivotally mounted upon the engine block as shown at 37. The plates 36 are engaged by the 100 outer ends of valve rods 38 which operate through suitable valve guides and have their inner ends engaged by tappets 39. The inner valves 34 also have their stems surrounded by springs 35, while pivotally mounted plates 40 engage the ends of these stems. The plates 40 are engaged and actuated by 105 valve rods 41 which also operate in suitable guides and these rods 41 are engaged by valve tappets 42.

The tappets 39 and 42 extend through suitable guides provided in the housing 27

and their inner ends are connected by cams 43 which are mounted upon cam shafts 44. The shafts 44 are driven from the crank shaft 30 by means of gearing 45.

It will be apparent from the foregoing description and accompanying drawings that the engine provides an exceedingly simple construction and is arranged so that the force of the expanded gases upon one piston 10 will act to increase compression in the chamber 16 at the opposite end of the cylinder and thus increase the power and efficiency of the engine. Compression between the pistons 23 is relieved by pressure relief 15 ports 46 which communicate centrally with each of the cylinders 10.

The invention is susceptible of various changes in its form, proportions and minor details of construction and the right is herein 20 reserved to make such changes as properly

fall within the scope of the appended claim. Having described the invention what is claimed is:

In an internal combustion engine, a block, a head fitting the block, the said block having inlet and exhaust ports and spark plug openings in the sides of the block, a single piston rod in each cylinder, two separate pistons carried on each rod, one firing on the up-stroke and the other on the down-stroke, 25 and a means connecting the piston rods with the crank shaft, the said valve mechanism, intake and exhaust ports being carried entirely on the sides of the engine so that the head is entirely free of any encumbrance. 30
In testimony whereof we affix our signatures.

FRANK H. WOOD.
FRED C. BARNARD.
